PHOTOGRAPHIC FLASH GUN

Yoshitaro Kaneko, Tokyo, Japan, assignor to U.S. Photo Supply Co., Inc., Washington, D.C., a corporation of Delaware

Application September 24, 1959, Serial No. 57,659

Term of patent 14 years

(Cl. D61—1)

FIG.1.

FIG.2.

FIG.3.

FIG.4.

FIG. 5.

FIG. 6.

Fig. 1 is a left side elevational view of a photographic flash gun showing my new design.

Fig. 2 is a front elevational view thereof.

Fig. 3 is a right side elevational view thereof.

Fig. 4 is a rear elevational view thereof.

Fig. 5 is a top plan view thereof.

Fig. 6 is a bottom plan view thereof.

The dominant features of my new design are shown in solid lines in the drawing. A portion of Fig. 2 is diagonally lined to indicate transparency.

I claim:

The ornamental design for a photographic flash gun, as shown and described.
